(57) **CLAIM**

The ornamental design for a foldable speaker, as shown.

DESCRIPTION

FIG. 1 is a front elevational view of a foldable speaker showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front-right-top perspective view thereof;

FIG. 8 is a perspective view showing a use thereof in the open state, the areas shown in broken lines are being depicted for illustrative purposes and form no part of the claimed design; and,

FIG. 9 is a perspective view showing the folded state thereof.
